CLAIM

The ornamental design for a cut stone, as shown and described.

DESCRIPTION

FIG. 1 is a front perspective view of a first embodiment of a cut stone showing our new design therefor;

FIG. 2 is a bottom plan view thereof;

FIG. 3 is a side elevational view thereof, the opposite side, front and rear elevational views being identical thereto;

FIG. 4 is a top plan view thereof;

FIG. 5 is a front perspective view of a second embodiment of a cut stone showing our new design therefor;

FIG. 6 is a bottom plan view thereof;

FIG. 7 is a side elevational view thereof, the opposite side, front and rear elevational views being identical thereto;

FIG. 8 is a top plan view thereof;

FIG. 9 is a front perspective view of a third embodiment of a cut stone showing our new design therefor;

FIG. 10 is a bottom plan view thereof;

FIG. 11 is a side elevational view thereof, the opposite side, front and rear elevational views being identical thereto; and,

FIG. 12 is a top plan view thereof.
